US0D1055632S

(12) **United States Design Patent** (10) **Patent No.:** **US D1,055,632 S**
(45) **Date of Patent:** **** Dec. 31, 2024**

(54) **REUSABLE FILTER CARTRIDGE**

(71) Applicant: **Universal Coffee LLC**, La Mirada, CA (US)

(72) Inventors: **Jennifer Shannon Lemmer**, Seattle, WA (US); **Ralph Wegener Satterlee, Jr.**, Seattle, WA (US); **Ronald Ralph DeMiglio**, Sun City West, AZ (US)

(73) Assignee: **Universal Coffee LLC**, La Mirada, CA (US)

(**) Term: **15 Years**

(21) Appl. No.: **29/772,194**

(22) Filed: **Feb. 26, 2021**

(51) LOC (14) Cl. **07-06**

(52) U.S. Cl.

USPC **D7/400**

(58) **Field of Classification Search**

(57) **CLAIM**

The ornamental design for a reusable filter cartridge, as shown and described.

DESCRIPTION

FIG. 1 is a perspective view of a reusable filter cartridge, showing our new design.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

The dot-dot broken lines in the drawings depict portions of the reusable filter cartridge that form no part of the claimed design.

1 Claim, 7 Drawing Sheets
